The ornamental design for a confectionery packaging box, as shown and described.

U.S. PATENT DOCUMENTS

DESCRIPTION

D. 288,062 * 2/1987 Aronson D9/337
D. 351,104 * 10/1994 Kapp D9/433
D. 385,781 * 11/1997 Levine et al. D9/432
1,913,950 * 6/1933 Platt 206/459.5

FIG. 1 is a top plan view of a front face of a confectionery packaging box, embodying my new design; and, FIG. 2 is a front elevational view of the side panel thereof. The broken lines shown in FIGS. 1 and 2 are for the purpose of showing environmental structure only and form no part of the claimed design.
